DOOR OPERATING MECHANISM

Robert J. Parsons, Schenectady, and Frederick Kunst van Almelo, Nassau, N. Y., assignors to Consolidated Car-Heating Company, Inc., Albany, N. Y., a corporation of New York

Application December 27, 1938, Serial No. 247,898

1 Claim. (Cl. 268—30)

This invention relates to closure operators, especially to door operating mechanism, and more particularly to a mechanism for operating the door of a vehicle, such as a street car or a bus.

5 A known type of door for such vehicles of the class in which a passenger entrance closed by the door is usually approached by one or more steps confined within the side of the vehicle, comprises a leaf or leaves of the door carried upon an arm 10 which swings about an upright axis in such a manner that the door leaf is moved bodily from a closed position in which the door is substantially parallel with the side of the vehicle, to an open position in which the door stands at an angle, usually at right angles, to the side of the car, the door extending inwardly from the car side.

When a vehicle of this character is filled to capacity, or whenever passengers crowd the platform, there is considerable difficulty in effecting such a transposition of the door from closed to open position and vice versa without interference with one or more of those passengers who stand near the steps, and various expedients have been 20 tried to avoid such interference, but not with entirely satisfactory results, for various reasons, among which may be noted particularly the inadequacy of existing means to cause the leading edge of the door to move in such a path that it at 25 no time projects in an undesirable direction into the space occupied by passengers.

Under such conditions, an object of the present invention is to provide, in place of the inadequate existing door-operating mechanisms, an improved 30 form of door operator by which the desired transposition of the door, in either the opening movement or the closing movement thereof, is effected rapidly and steadily, so that the leading edge at no time so projects within the sides of the vehicle 35 as to interfere with passengers or so as to be itself prevented by the presence of passengers from working properly.

In pursuance of the above general object, a further object is to provide a member associated 40 with the door frame, and acting positively in co-operation with a complementary member carried by the door adjacent to its pivot, so as to cause the requisite turning movement of the door around its pivot by translation of a geared inter- 45 action of said members into a rotative moment exerted upon the door as it is moved bodily in preferably conventional fashion by a suitable motor under the control of the motorman or some other car guard.

50 Another object is to provide a sturdy flexible

actuating element for the above purpose which preferably takes the form of a sprocket chain attached to a non-rotating sprocket wheel segment which is mounted in fixed position coaxially with respect to upright axis around which oscillates the arm upon which the door is pivoted, the sprocket chain or other flexible member having a loop which is engaged with a sprocket wheel or pulley on the door, surrounding the door pivot so that when the arm is swung to move the door 10 bodily, the sprocket chain serves as a flexible track within which the door sprocket wheel runs, causing the door to turn in the desired manner.

5 Other objects and features of the invention will appear as the description of the particular physical embodiment selected to illustrate the invention progresses.

In the several views included in the drawing, like characters of reference have been applied to corresponding parts throughout the drawing, in 20 which:

Figure 1 is a view in horizontal section, partly in plan, illustrating a car door operating mechanism in the construction of which the present invention has been embodied, the door being 25 shown in somewhat diagrammatic fashion in its closed position, shown in full lines, and also in its open position, shown in dash-dot lines; Fig. 2 is a fragmentary detail view in vertical section of the same parts, with the door shown in elevation in 30 its closed position, the related parts of the doorway and door operating mechanism being shown in their appropriate relative positions; Fig. 3 is a fragmentary detail view similar to Fig. 1, but showing the door and associated door-operating 35 mechanism in a partially open position of the door.

In a particular physical embodiment of the invention selected for illustration and description, the part designated generally by the reference 40 character 11 is a doorway, forming part of the body structure of an electric street-railway car, and including an overhead lintel plate 12 which serves as a base for a suitable motor, not shown, but which may be desirably of a known fluid- 45 pressure type, adapted to cause oscillative rotation of a vertical door-shaft 13 around an upright axis, thereby rocking an arm 14 to and fro through an arc of substantially 90 degrees, the arm being fixed to the shaft as by a pin 15, only 50 so much of the above parts being shown as is necessary to permit a proper understanding of the invention.

55 Part of a door is shown, in outline, comprising, preferably, complementary leaves 16, 17, of which 55

only the leaf 16 is illustrated in detail, it being understood that if a pair of leaves be provided, the leaf 17 may be symmetrical with 16 in all essential particulars, and similarly operated, so that only the leaf 16 will be described, with the associated mechanism for operating it, to permit complete understanding of the invention.

Each leaf, as 16, is suitably mounted pivotally on its arm 14, as by a pivot post 18, in the instance illustrated, provided with attaching wings 19 bolted or riveted to the door 16 as indicated in Fig. 2, the pivot post extending upward through suitable bearings 20 in the free end of the arm 14, above which it is provided with a sprocket gear 21, by which the post and door are held in dependent relation upon the arm, and by means of which gear the door can be rotated around the axis of pivot post 18.

In pursuance of the invention, in the embodiment illustrated, the turning movement of the door 16 is effected by the coaction of sprocket wheel 21 with the loop 22 of a sprocket chain 23 which is free to swing with the sprocket wheel 21, post 18 and door 16, as the transposition of the latter bodily from the full-line closed position to the dash-dot open position is effected by oscillation of shaft 13 and arm 14 in one direction or the other, this being effected in conventional manner, as through a pinion 9, fast on shaft 13, 30 the pinion meshing with any suitable gearing actuated by a known form of motor (not shown) which may be mounted on the base plate 12.

The plate 12 serves also as a support for a segmental sprocket gear member 24, which may 35 desirably be formed integrally with a boss 26 of a fitting 27 mounted upon plate 12 and having an upper boss 28 in which is journaled the upper end of the door shaft 13. A boss 25 extends upward from the arm 14 within the boss 26 and around the shaft 13. The segmental gear 24 40 serves as a track engaged flexibly by the end portions 29, 30 of the chain 25.

The chain is shown as fastened to the periphery of the sprocket 24, as by screws 31, so that the 45 sprocket chain has no capacity for longitudinal movement, and when the shaft 13 turns the arm 14 and swings the door around from its closed, full-line position to its dash-dot position, both shown in Fig. 1, the sprocket 21 upon the door post 18 runs within the loop 22 of sprocket chain 50 23, with the result that the door is turned through about 90 degrees from its closed position parallel with the door aperture to a position which in practice is substantially parallel with the end wall 55 W of a car, for example a wall between the passenger compartment and a vestibule.

In the course of such transposition, the door is turned serially through successive positions, of 60 which one is illustrated in Fig. 3, the leading edge 32 of the door being swung out of the plane of the doorway, while the trailing end 33 remains approximately in that plane throughout the transposition of the door.

It will be understood that the displacement of 65 the leading edge 32 from said doorway starts rapidly, then proceeds with less rapidity, then speeds up again and eventually slows down to zero as the complete angular change is realized, and this mode of operation is desirable, as the initial 70 movement of the door is adapted to attract the attention of passengers who are thus warned to avoid interference with movement of the door.

Provision is made of means to make compact and to insure a snug engagement of the chain 75 23 with its cooperating sprocket wheels 21 and 24,

and for this purpose an idler sprocket wheel 34 is illustrated, mounted on a stud 35 carried by the arm 14. A coupling sleeve 36 is also provided, to adjust the length of the chain without disturbing the screws 31 by which its ends are secured to 5 sprocket wheel segment 24.

From the foregoing it will be seen that in the operation of the device, the door 16 is so turned upon its pivot 18 during transposition of the door bodily from its full-line closed position to its 10 open position that the swinging departure of the leading edge 32 from the doorway occurs at a region of the doorway adjacent to the end wall W of the car within the vestibule, where such movement is least likely to disturb the passengers in 15 the vicinity of the doorway, so that this initial turning movement of the door may be utilized with safety to advance the edge 32 as rapidly as possible along the wall W.

Then, when the arm has swung around past 20 the position shown in Fig. 3, the edge 32 may be advanced in an edgewise direction with greater safety than is usual with door-openers of this general class, by reason of the fact that the door edge will move relatively slowly in its edgewise 25 direction, owing to the above described organization of the elements so that the pivot axis 18 then swings in toward the wall W rather than away from the plane of the doorway.

Applicant desires to have it understood that 30 whereas the member 23 has been illustrated as a chain or sprocket chain and the member 21 as a sprocket wheel and the member 24 has been called a sprocket wheel although it has not been illustrated with any teeth therein and although 35 member 34 has been illustrated and described as a sprocket wheel, it is to be understood that these several parts are merely illustrative and that the particular construction shown for illustration and the particular terms used as descriptive of the several parts is not intended to exclude the use of a plain ribbon in place of the so-called sprocket chain 23 or the use of a plain disc in the place of the sprocket wheel 21 or the use of a plain disc in place of the sprocket wheel 45 34 or the use of a toothed sprocket wheel 24 as these several parts enumerated as well as those illustrated and described are all substitutes one for the other insofar as applicants' invention is concerned and that the terminology used is intended to imply and include both the form illustrated and the form which may be used as a substitute therefor.

Although we have particularly described one 55 particular physical embodiment of our invention and explained the operation, construction and principle thereof, nevertheless, we desire to have it understood that the form selected is merely 60 illustrative, but does not exhaust the possible physical embodiments of the idea of means underlying our invention.

What we claim as new and desire to secure by Letters Patent of the United States, is:

A door operator unit of the class described, 65 adapted to operate in conjunction with a door, a doorway having a lintel or overhead plate and a motor mounted on said plate, also with a door shaft journaled in a bearing carried by said plate and oscillatable about an upright axis adjacent to one side of the doorway; said unit comprising an arm fixed upon said shaft and having at its free end a pivot means to support a door-leaf in position to close said doorway, and also adapted to carry said leaf bodily around through 70 an arcuate path of about 90 degrees; and means 75

to rotate said door relatively to the plane of the doorway concurrently with said transposition bodily, said door-rotating means being characterized by a chain formed into a loop extending alongside of said arm, a sprocket wheel fixed upon said door pivot and engaged with said loop, the chain having two stretches extending toward the axis of said door-shaft and anchored at a region eccentric to said shaft, and a segmental 5 sprocket wheel part mounted upon said plate-bearing coaxially with respect to said shaft, said two ends of the sprocket chain being anchored to opposite sides of the circumference of said

segmental sprocket wheel part, so that when said arm is swung by rotation of said shaft said pivot-sprocket wheel will run along said chain, within the loop thereof and will be rotated, thereby turning the door relatively to the plane of the 10 doorway, an adjustable coupling interposed in said sprocket chain and a further sprocket wheel carried by said arm and cooperating with said chain to maintain said chain in snug engagement with said pivot sprocket wheel. 10
